CLAIM

The ornamental design for a protective case for earphone, as shown and described.

DESCRIPTION

FIG. 1 is a front, right and top perspective view of a protective case for earphone, showing my new design; FIG. 2 is a rear, left and bottom perspective view thereof; FIG. 3 is a perspective view thereof, shown in an open state; FIG. 4 is a front view thereof; FIG. 5 is a rear view thereof; FIG. 6 is a left side view thereof; FIG. 7 is a right side view thereof; FIG. 8 is a top plan view thereof; and, FIG. 9 is a bottom plan view thereof.

The broken lines shown in the drawings illustrate portions of the protective case for earphone that form no part of the claimed design.
